(57) **CLAIM**

The ornamental design for a wooden greeting card as shown and described.

DESCRIPTION

FIG. 1 is a front, bottom, and right perspective view of the wooden greeting card showing my new design in a completely folded position;

FIG. 2 is another front, bottom, and right perspective view thereof, in a completely folded position;

FIG. 3 is another front, bottom, and right perspective view thereof, in a completely folded position;

FIG. 4 is a top view of FIG. 1;

FIG. 5 is a front view thereof;

FIG. 6 is a bottom view thereof;

FIG. 8 is a top view of FIG. 3;

FIG. 9 is a front view thereof;

FIG. 10 is a bottom view thereof;

FIG. 11 is a rear view of FIG. 1;

FIG. 12 is a left side view of FIG. 1;

FIG. 13 is a right side view of FIG. 1;

FIG. 14 is a front-top perspective view of the wooden greeting card in a slightly open position of FIG. 2;

FIG. 15 is a front-top perspective view of the wooden greeting card in a slightly open position of FIG. 3; and,

FIG. 16 is a front-top perspective view of the wooden greeting card in a slightly open position of FIG. 3.

The broken line showing of portions of the wooden greeting card in FIGS. 3, 4, 6-11, 14-16 is included for the purpose of illustrating environmental structure and forms no part of the claimed design.
